ATTORNEY'S.

UNITED STATES PATENT OFFICE.

MORTIMER G. MERRITT, OF ROME, NEW YORK, ASSIGNOR TO THE ROME METALLIC BED COMPANY, OF SAME PLACE.

DESIGN FOR A BEDSTEAD.

SPECIFICATION forming part of Design No. 25,929, dated August 11, 1896.

Application filed July 11, 1896. Serial No. 598,898. Term of patent 3½ years.

To all whom it may concern:

Be it known that I, MORTIMER G. MERRITT, a citizen of the United States, residing at Rome, in the county of Oneida and State of New York, have invented and produced a new and original Design for Bedsteads, of which the following is a specification, reference being had to the accompanying drawing, showing the same.

10 The drawing shows a perspective view of my design of bedstead.

This bedstead is what is known as a "metallic" bedstead, and the leading features of my design consist of a rectangular frame *a*, supported by diagonal bars *b* in the upper extended portions of the legs, forming the head and foot boards, respectively, together with an ornament *c* at the union of the diag-

onal bars with the corners of the frame mentioned.

Further features of the design consist in the cross-bars between the upper ends of the legs, which, together with the legs, surround the frame mentioned, the lower one of which is connected to the frame by an ornamental joint *d*. 20 25

What I claim is—

The design for a bedstead herein shown and described.

In witness whereof I have affixed my signature in presence of two witnesses. 30

MORTIMER G. MERRITT.
